UNITED STATES PATENT OFFICE.

REXFORD M. SMITH, OF WASHINGTON, DISTRICT OF COLUMBIA, ASSIGNOR TO CONNECTICUT AIRCRAFT COMPANY, OF NEW HAVEN, CONNECTICUT, A CORPORATION.

FLYING-MACHINE.

1,288,721.

Specification of Letters Patent.

Patented Dec. 24, 1918.

Original application filed January 2, 1912, Serial No. 669,003. Divided and this application filed January 12, 1915, Serial No. 1,780. Renewed May 29, 1918. Serial No. 237,370.

To all whom it may concern:

Be it known that I, REXFORD M. SMITH, a citizen of the United States, residing at Washington, in the District of Columbia, have invented new and useful Improvements in Flying-Machines, of which the following is a specification.

This invention relates to flying machines of that class in which the machine is supported in flight by the dynamical reactions of the air upon one or more sustaining surfaces, and particularly to an improved construction of sustaining surface and flexible wing tips or balancing devices, with means for controlling the same to maintain lateral stability, whereby certain advantages are gained in the control of the machine.

The present invention is a division of my prior application No. 669,003, filed on January 2, 1912, Patent No. 1128379, dated Feb. 16, 1915, and is directed particularly to the subject matter of the construction of the lower plane and associated balancing elements disclosed but not particularly claimed in such prior application.

The invention consists in the features of construction, combination and arrangement of parts hereinafter described and claimed, reference being had to the accompanying drawings forming a part thereof, in which:

Figure 1 is a rear perspective view of a biplane sustaining surface, one of the planes of which is provided with the improvements constituting my invention; and

Figs. 2 and 3 are views of the lower plane illustrating the balancing actions.

In the illustrated exemplification the invention is shown embodied in a biplane machine, although it is to be understood that it is not limited thereto, as the essential features thereof may be employed with equal efficiency upon other types of multiplane machines or upon machines of the monoplane type.

Referring to the drawing 1 and 2 designate the upper and lower supporting planes or surfaces of a biplane structure as disclosed, each comprising a pair of wings 3 and 4 spaced at their inner or proximate edges to provide a fore-and-aft air gap 5.

These gaps are arranged in the path of the air impelled upwardly and downwardly and traveling rearwardly from the propeller, thus permitting the disturbed air to have free vent through the supporting surfaces and preventing the same from disturbing the air compressed by the wings, accumulating between the supporting surfaces and increasing the head resistance, or varying the angle of incidence or flying attitude of the machine.

The wings, which have a suitable fore-and-aft lifting curvature, are formed of a fabric or other suitable material secured to a frame structure of proper character, the trail portions of the wings in rear of the dotted lines 6 being flexible for a vertical vibratory air shedding action. The planes may be mounted upon the nacelle, fuselage or main frame of the machine in any suitable manner and suitably secured and braced.

The wings of the supporting surfaces are symmetrically curved, and the flexible rear portions of the respective wings are bisected or divided in a fore-and-aft direction, as at 7, forming relatively rigid and flexible inner and outer portions, which normally lie in alinement, the inner rigid portions 8 being vibratory only for an air shedding action, while the outer flexible portions 9, 10, 9^a and 10^a, which normally lie in the plane of and form a part of the supporting surface, are movable vertically for balancing actions.

Each wing thus comprises a body having a rigid fore-portion and a flexible rear portion, the latter consisting of an inner section normally uncontrolled and adapted to flex or vibrate under air pressures, and an outer section adapted to be positively controlled and adjusted to maintain the lateral balance of the machine. The ailerons, balancing planes or wing tips 9 and 10 are capable of being flexed downward and only to a positive angle of incidence, and constitute no part of the present invention, while the wing tips, ailerons or balancing planes 9^a and 10^a are capable of being flexed upward only to a negative angle of incidence and

constitute, with the associated control devices, the subject matter of the present invention, the features which are not claimed herein forming the subject matter of the 5 claims of my aforesaid prior application of which this application is a division.

The wing tips or ailerons are designed to be operated by a pair of right and left hand controlling levers 11 and 12, each universally mounted or intermediately pivoted to 10 swing fore-and-aft on an axis 13 and to swing laterally on an axis 14, said levers being so relatively arranged as to be operated independently or in unison. The 15 lower arm of the lever 11 has attached thereto a wire or cable 15 leading over guide pulleys 16 to a point above the wing tip or aileron 10^a, and the upper arm of said lever has attached thereto a wire or cable 17 leading 20 over one or more guide pulleys 18 to a point below the wing tip or aileron 10, said cables 15 and 17 being respectively attached by branches or bridles 15^a and 17^a to the outer corner portions of the respective wing 25 tips or ailerons, whereby when the lever 11 is swung laterally to the right the wire 17 will be relaxed while the wire 15 will be drawn upon to bend or flex the aileron or wing tip 10^a upward to a negative angle of 30 incidence; and whereby when said lever is swung laterally to the left the wire 15 will be relaxed while the wire 17 will be drawn upon to bend or flex the aileron 10 downward to a positive angle of incidence. The 35 lever 12 is similarly connected by correspondingly designated controlling connections with the ailerons or wing tips 9 and 9^a, so that when said lever is swung laterally to the left the wire 17 will be relaxed and the 40 wire 15 drawn upon to bend or flex the aileron or wing tip 9^a upward to a negative angle of incidence, while upon a reverse lateral motion of said lever the wire 15 will be relaxed and the wire 17 drawn upon to 45 bend or flex the aileron or wing tip 9 downward to a positive angle of incidence.

It will thus be understood that the ailerons at each side may be independently flexed by the control levers, and as said ailerons are 50 capable of being flexed in pairs upward and downward at right and left hand sides of the machine, in a plane perpendicular to the plane of the supporting surface, it will be evident that in balancing and banking the 55 machine the adjustment of the ailerons to positive angles of incidence at the opposite sides of the machine will result in securing increased efficiency of balancing control, since a positive lifting action will be 60 obtained at one side and a positive depressing action at the other side. By this means the well known objections to constructions in which one balancing surface is drawn down to secure a lift and the opposite 65 surface merely released to assume a negative

angle of incidence, are avoided. Moreover, since the wing tips or ailerons are movable perpendicularly to the plane of the supporting surfaces, they are adapted to be adjusted without affecting or destroying the 70 normal symmetry of said surfaces, thus preventing the same from being unduly strained warped out of shape or setting up an undue head resistance, as in constructions of that kind in which the surfaces are helicoidally 75 bent or warped.

In practice, the levers 11 and 12 are arranged to be grasped in the right and left hands of the operator, so that they may be independently or simultaneously adjusted so 80 that instinctive motions on the part of the operator will result in a proper adjustment of the balancing surface. The foregoing description applies to the construction as specifically disclosed and applied to a biplane 85 surface, but the features of the present invention reside solely in the construction of the wings and ailerons or wing tips of the lower supporting surface 2, in which the flexible wing tips or ailerons 9^a and 10^a are 90 flexible in an upward direction only to a negative angle of incidence, the tips of the respective wings being independently adjustable through the operation of the respective levers. It will be understood, of 95 course, that this structure may be employed in a biplane machine in which the upper supporting plane is devoid of balancing surfaces, or in any other type of multiplane machine, or in a monoplane structure. It 100 will thus be evident that when the machine dips laterally in either direction to an unbalanced position, the aviator may regain control by simply adjusting the aileron or wing tip at the high side of the plane 2 upward to a negative angle of incidence, leaving 105 the aileron or wing tip at the low side in its normal position.

By making the wing tips flexible perpendicularly they may be bent or warped for 110 balancing effect without destroying the symmetry of the plane, with obvious advantages. By making the wing tips adjustable upwardly only to a negative angle of incidence, and rendering said wing tips independently adjustable, the wing tip at the 115 high side of the laterally unbalanced machine may be adjusted upward without regard to the other wing tip, by which the effective area and angle of incidence at the 120 high side will be increased, while the effective area and angle of incidence at the low side remains unimpaired, so that the machine may be restored to a balanced position without setting up opposing resistances at 125 the opposite sides of the machine, without increasing the head resistance at either side, and without, therefore, establishing any condition under which there is a tendency of the machine to oscillate back and forth on its 130

vertical axis. Furthermore, the balancing mechanism is simplified in construction and rendered more reliable and efficient in action.

Having thus described my invention, I claim:

1. A supporting surface for flying machines comprising an aeroplane having a lifting curvature in a fore-and-aft direction, the wings of said plane being disposed in the same horizontal plane and provided at the corners of their trailing edges with correspondingly curved ailerons forming parts of the plane and normally arranged within the plane thereof, said ailerons having movement in an upward direction only from a normal position beyond the plane of the supporting surface being independent of operating connection with each other, and being automatically movable to normal position after actuation, and operating means for moving said ailerons to a negative angle of incidence in an upward direction, said operating means operative for separately and independently adjusting said ailerons.

2. A supporting surface for flying machines comprising an aeroplane having a lifting curvature in a fore-and-aft direction, said plane being of oblong rectangular form and of greater length than width and having its wings disposed in the same horizontal plane and its lead and trailing edges arranged in parallel relation, the trailing portions of the wings of said plane being provided adjacent their lateral margins with ailerons forming part of the plane and curved to conform thereto and normally arranged within the plane of said aeroplane, said ailerons being separate from and independent of operative connection with each other, automatically movable after actuation to normal position, and operable only in an upward direction from such position to a negative angle of incidence relative to the plane of the aeroplane, and means for separately and independently moving each aileron in an upward direction to a negative angle of incidence as set forth.

3. A supporting surface for flying machines comprising an aeroplane having all of its portions disposed substantially in the same horizontal plane and formed with a fore-and-aft lifting curvature, said aeroplane having its trailing half provided with an inadjustable central portion having a limited degree of flexibility under wing pressure, and ailerons at the lateral extremities of the trailing portion of greater flexibility than said central portion and flexible in an upward direction only to a negative angle of incidence relative to the plane of the aeroplane, said ailerons being normally arranged in the plane of the aeroplane and curved to conform thereto and forming part thereof and automatically movable to normal position after actuation and immovable below

the plane of the aeroplane, and means for separately and independently adjusting the respective ailerons.

4. A supporting surface for flying machines comprising an aeroplane having all of its portions disposed substantially in the same horizontal plane and formed with a lifting fore-and-aft curvature, said aeroplane being provided with ailerons at the outer margins of the trailing portions thereof, said ailerons being normally arranged in the plane of the aeroplane and curved to conform thereto and forming part thereof and being immovable from a normal position below the plane of the aeroplane and movable in an upward direction only to a negative angle of incidence above the plane of the aeroplane and adapted to automatically return to normal position after actuation, and means for independently operating the respective ailerons, said means embodying devices for transmitting an upward pull to each aileron, each of said devices including branching connections coupled to the aileron on opposite sides of the center thereof.

5. A supporting surface for flying machines comprising an aeroplane having all of its portions disposed substantially in the same horizontal plane and formed with a lifting curvature in a fore-and-aft direction and having its trailing portion provided with ailerons at or near the lateral margins thereof, said ailerons being normally arranged in the plane of the aeroplane and curved to conform thereto and forming part thereof and being immovable downwardly from a normal position below the plane of the main plane and movable from a normal position in an upward direction only to a negative angle of incidence relative to the plane of the aeroplane, each aileron being adapted to automatically return to normal position after actuation, and separate and independent levers and connections for separately and independently adjusting the respective ailerons.

6. A supporting surface for flying machines comprising an aeroplane having all of its portions disposed substantially in the same horizontal plane and formed with a fore-and-aft lifting curvature and having its trailing portion provided with ailerons at the lateral margins thereof, said ailerons being normally arranged in the plane of the aeroplane and curved to conform thereto and forming part thereof and immovable downwardly from a normal position below the plane of said aeroplane and movable in an upward direction only from a normal position to a negative angle of incidence relative to the plane of the aeroplane, each aileron being adapted to automatically return to normal position after actuation, and separate and independent levers and connections

for separately and independently moving said ailerons upwardly, said levers being arranged for instinctive controlling motions on the part of the operator.

- 5 7. A supporting surface for flying machines comprising an aeroplane having all of its portions disposed substantially in the same horizontal plane and formed with a lifting curvature in a fore-and-aft direction,
 10 said aeroplane having its trailing portion provided with bisections on opposite sides of its center forming an inadjustable comparatively inflexible central trail portion and ailerons at the lateral margins of the
 15 wings of the aeroplane, said ailerons being curved to conform to and forming part of the structure of the aeroplane and being normally arranged in the plane thereof, said ailerons being immovable from a normal
 20 position below the plane of the aeroplane and movable in an upward direction only to a negative angle of incidence above the plane of the aeroplane, and controlling devices for manually actuating the respective ailerons,
 25 said controlling devices being arranged for separately and independently actuating said ailerons and capable of transferring upward movement thereto only.

8. A supporting surface for flying machines comprising an aeroplane of oblong rectangular form with all of its portions disposed substantially in the same horizontal plane and having straight parallel leading and trailing edges, the trailing portion
 30 of the plane having a downward and rearward curvature, and said trailing portion of the plane being provided in its wing portions with fore-and-aft bisections, forming a rigid and inflexible portion at the center
 35 of the aeroplane and flexible portions at the lateral margins of the aeroplane, said flexible portions forming ailerons constituting a part of the aeroplane curved to conform thereto and normally arranged in the plane
 40 thereof, said ailerons being immovable in a downward direction below the plane of the aeroplane and movable in an upward direction only to a negative angle of incidence above the plane of the aeroplane and automatically
 45 movable to normal position after actuation, and controlling devices for separately and independently actuating the respective ailerons and operative for moving said ailerons upwardly only and inoperative
 50 for moving them downwardly.

9. A supporting surface for flying machines comprising an aeroplane having all of its portions substantially in the same horizontal plane and formed with a fore-and-aft lifting curvature, said aeroplane being provided with ailerons normally forming a part of said aeroplane and curved to conform thereto and arranged in the plane thereof, said ailerons being movable in an upward direction only to a negative angle

of incidence, and flexible up-pulling controlling connections for separately and independently adjusting said ailerons in an upward direction only.

10. A supporting surface for flying machines comprising an aeroplane of oblong rectangular form having all of its portions disposed substantially in the same horizontal plane and formed with a fore-and-aft lifting curvature, said aeroplane being provided with parallel leading and trailing edges, the trailing portion of said aeroplane being downwardly and rearwardly curved, said trailing portion being bisected in a fore-and-aft direction between the center and lateral margins of the aeroplane and forming a central comparatively inflexible portion and lateral flexible portions constituting ailerons, the said ailerons being movable only in an upward direction to a negative angle of incidence and immovable in a downward direction beyond a normal position below the plane of the aeroplane, said ailerons being curved to conform to and constituting integral parts of the plane structure, and separate and independent devices for adjusting said ailerons in an upward direction only and incapable of adjusting them downwardly.

11. A supporting surface for flying machines comprising an aeroplane having a fore-and-aft, downward and rearward lifting curvature, the wings of said aeroplane being disposed in a substantially horizontal plane and provided at the outer lateral margins of their trailing edges with correspondingly curved ailerons forming integral portions of the aeroplane and normally arranged within the plane thereof, said ailerons being independent of controlling connection with each other and adjustable vertically for stabilizing action from a normal position in a single direction only beyond the plane of the aeroplane and inoperative in the reverse direction beyond the plane of the aeroplane, and means constrainedly operative for separately and independently adjusting said ailerons.

12. A supporting surface for flying machines comprising an aeroplane having a fore-and-aft, downward and rearward lifting curvature, the wings of said aeroplane being disposed in a substantially horizontal plane and provided at the outer lateral margins of their trailing edges with correspondingly curved ailerons forming integral portions of the aeroplane and normally arranged within the plane thereof, said ailerons being independent of controlling connection with each other and adjustable vertically for stabilizing action from a normal position in a single direction only beyond the plane of the aeroplane and inoperative in the reverse direction beyond the plane of the aeroplane, and means constrainedly

operative for separately and independently adjusting said ailerons solely in the directions of their movement beyond the plane of the aeroplane, said ailerons being automatically movable by air pressure after actuation back to normal position.

In testimony whereof I affix my signature in presence of two witnesses.

REXFORD M. SMITH.
